RECOILLESS GUN

Kenneth R. Fowler, Warren, Pa.

Application December 12, 1946, Serial No. 715,674

4 Claims. (Cl. 89—1.7)

This invention relates to improvements in recoilless weapons, particularly air-cooled single-loading recoilless guns for firing fixed ammunition as distinguished from those weapons firing rocket-propelled or jet-propelled ammunition.

An object of this invention is to provide a recoilless gun in which parts thereof are readily demountable for transportation and are capable of being quickly assembled. Another object is to provide a recoilless gun of light weight and easy operation with a locking sleeve carrying an interrupted thread, the sleeve being lighter in weight and easier to rotate and translate than is the gun body of its breechblock. A further object is to provide a stop for the breechblock when it has been moved from an out-of-the-way position for loading to a position in which it is aligned with the gun axis.

Recoilless guns as a class are generally of lighter weight than recoil type guns of the same caliber and this has enabled recoilless guns to be more easily transported. This invention makes such recoilless guns still more easily transportable by making some of their parts easily demountable and readily assembled. To accomplish this result, the breechblock is easily removable from the gun body and from an actuating shaft for it. This shaft and also the trunnions with their band are likewise removable from the gun body or front gun section. Instead of rotating either the breechblock or gun body preparatory to opening the breech, a sleeve of lighter weight than either the breechblock or gun is provided with an interrupted thread engaging a cooperative thread on the breechblock and this sleeve is rotated and then subjected to translation in order to release a connection before the breechblock is moved out of the way. Inasmuch as the breechblock is heavier than some other gun parts as shown by the drawing, a projection from the sleeve is provided with an interrupted thread and engages the groove between threaded portions of the breechblock to act as a stop and align the sleeve and breechblock before the latter is subjected to a relative rotation for closing the breech.

Ammunition for the present type of weapon consists of a cartridge case having the usual projectile, but the rear or base of the cartridge is closed by a frangible cap. When the ammunition is fired, which is done electrically, the projectile moves forwardly through the barrel in the conventional manner, but the frangible cap is disintegrated and forced rearwardly, allowing some of the propellant gases to escape through the recoil-eliminating venturi openings.

This form of ammunition is described in copending application Serial No. 715,675, filed December 12, 1946, for Ammunition for Recoilless Guns, now Patent 2,492,279 dated December 27, 1949.

The foregoing and other objects of the invention as well as the exact nature thereof will be apparent by reference to the following description of the accompanying drawings in which:

2

Figure 1 is an elevational view of the gun detached from its mount;

Figure 2 is a longitudinal vertical central sectional view through Figure 1, showing the gun preparatory to firing, 5 loaded with a round of ammunition, shown partially in section, and certain of the gun operating parts in sectional and others in plan views.

Figure 3 is a view similar to Figure 2, but showing the locking sleeve disengaged from the breechblock preparatory to opening the same for extracting an expended round of ammunition, shown in section.

Figure 4 is a view similar to Figure 2 but with the breechblock, shown in elevation, opened but not yet clear of the ammunition chamber.

Figure 5 is a plan view of Figure 1 but with the breechblock in an open position clear of the ammunition chamber;

Figure 6 is a transverse section taken on line 6—6 of Figure 2;

Figure 7 is a view similar to Figure 6 but showing the locking sleeve in a position preparatory to swinging the breechblock away from the ammunition chamber;

Figure 8 is a transverse section through line 8—8 of Figure 2;

Figure 9 is a bottom plan view of the locking sleeve; Figure 10 is a top view of the operating mechanism thru line 10—10 of Figure 3;

Figure 11 is an elevational view of the venturi orifices of the breechblock as viewed from the interior thereof and through which the propellant gases escape to neutralize recoil of the weapon;

Figure 12 is a sectional view through line 12—12 of Figure 11;

Figure 13 is a detail sectional view of the electrical firing mechanism;

Figure 14 is a sectional view through line 14—14 of Figure 10; and

Fig. 15 is a section through the breech end of the gun of Figs. 2 and 3.

The recoilless weapon of the invention consists generally of a barrel band 1 supporting a front gun section or barrel 2 having an ammunition chamber 3 closed by a rear section or breechblock 4 through a locking sleeve 5 actuated by an operating mechanism 6 depending from the barrel band 1. As shown in the drawing, the sleeve 5 is lighter in weight and therefore easier to move than the front or rear gun sections.

The barrel 2 integrally merges with the enlarged chamber 3 through a sloping portion 7, the chamber 3 being adapted to receive a cartridge case 3' of the type having a frangible cap 4' and an annular metallic ring 66 encircling the rear end portion of the case and insulated as described in copending U. S. application Serial No. 715,675, now Patent 2,492,279 dated December 27, 1949.

The chamber 3 has an integral circumferential flange 9, a machined cylindrical outer surface 10, and a locking notch 11 in its slope 7. The flange 9 has internally thereof an annular recess 9' for receiving the annular ring 66 of the cartridge case 3'.

The barrel 2 may be either smooth-bored or rifled, either being suitable for use in recoilless weapons of the instant type. However, practical experience has proven that results obtained with smooth bore barrels, as to accuracy and range, are far inferior to the results obtained with rifled barrels so that the latter are preferred.

The periphery of the barrel 2, adjacent the chamber slope 7, is provided with interrupted threads 12 (Fig. 2) for ready removal of the barrel band 1 and its attached shaft. This band 1 has a cylindrical portion 13 with internal interrupted threads 14 for meshing with the external threads 12. The top of the cylindrical mem-

ber 13, is provided with an upstanding lug 15, open slotted for receiving a threaded locking screw 16 having a pair of spaced integral collars 17 for straddling the lug 15. The screw 16 is thus held in the lug 15 against axial movement but free to be rotated by a handle 18 pivoted to the screw 16. A key 19, slidably mounted between a pair of spaced parallel guides 20, formed integral upon the cylindrical portion 13, is threaded to the screw 16. The key 19 has a tapered end and, through rotation of the screw 16, can be moved into and out of the tapered notch 11 in the chamber slope 7 as shown in Fig. 5; withdrawal of the key 19 from the notch 11 frees the barrel band 1 for rotation, to disengage the threads 12 and 14, and removal from the threaded portion 12 by movement longitudinally and muzzlewardly of the barrel.

Securely attached to the barrel band 1 are diametrically opposite trunnion pins 21 for supporting the gun in any suitable structure. The end of the key 19 engaging the side of the notch 11 assists in having the trunnion axis correctly positioned angularly.

Depending from the barrel band 1 is a bracket 22 of L-shaped cross section supporting a longitudinally extending abutment plate 23 and a tubular member 24 parallel to the barrel 2.

The tubular member 24 has its forward end closed by a threaded cap 25 and its rearward end terminating in a downwardly-directed stop member 26 having a radial flange 26' functioning in a manner to be described.

A shaft 27 is slidably and rotatably supported within the tubular member 24. The forward end of the shaft 27 is threaded at 28 to receive a threaded plug 29 having a flange 30 adapted to abut the threaded end 27' to limit excessive sliding movement of the shaft 27 to the rear.

For a purpose to be described, the shaft 27 is provided on its periphery with a transverse slot 29' and spaced therefrom a depression 29'', both slot 29' and depression 29'' adapted to receive a detent 23' slidably carried by a tubular portion intermediate the bracket 22 and the abutment 23. The detent 23' is forced by a spring 23'' into engagement with either the slot 29' or the depression 29'' for yieldably retaining the shaft 27 in either of two positions shown in Figures 3 and 4, respectively.

Anchored to the shaft 27 is a gear case 32 rotatably carrying a cross shaft 33 to which is secured a helical toothed pinion 34 meshing with an L-shaped rack 35 having teeth for cooperation with the pinion 34 and attached to the locking sleeve 5. A hand lever 31 is secured outside of and on the right in Fig. 1 of the gear case 32, it being secured to the cross shaft 33 for rotating the same. Figs. 2, 3, and 4 should not imply that this lever 31 is on the left or opposite side. The hand lever 31 is formed with an oppositely extending lug 31' for coaction with the flanged stop member 26' to prevent rotation of lever 31 when the same is swung from its Fig. 4 position to that shown in Fig. 5 and intermediate positions.

A shaft 36 is attached to the gear case 32 in alignment with the shaft 27. The shaft 36 is provided with a longitudinally extending rib or tooth 37 and a transverse plate 38 (Figs. 6 and 7). The shaft 36 terminates in an end portion 39, having an open-ended slot 40, for receiving the breechblock disconnect pin 59.

As shown in Figure 9, the locking sleeve 5 is formed with longitudinally spaced cylindrical portions 41, 42 and 43.

The forward cylindrical portion 41 slidably mounts the locking sleeve 5 on the ammunition chamber surface 10 and contains the L-shaped gear 35, having a longitudinal leg 44 and a transverse leg 45, which as previously explained is in mesh with the helical toothed gear 34 in firing position.

The intermediate cylindrical portion 42 has formed thereon a tapered portion 46 (Fig. 1) and a curved depression 46' (Fig. 9) to provide the necessary clearance for the helical toothed pinion 34 and its casing 32 at the

end of the travel of the gear 34 on the longitudinal leg 44. Motion of the sleeve 5 to the rear of the gun is limited by the internal shoulder 47 abutting the circumferential flange 9.

The rearward cylindrical portion 43 is provided on its underside with longitudinal teeth 48 and 49 (Fig. 9) adapted to engage the tooth 37. The rear end surface of the portion 43 is provided with a segmental groove 50 (Fig. 9) extending completely across tooth 49 and partially across tooth 48. A lug 51 (Figs. 1, 6 and 7) projects radially from the periphery of portion 43 at the end of the segmental groove 50 and opposite the tooth 48. The teeth 48 and 49, the groove 50 and the lug 51, cooperate with the longitudinal tooth 37 and transverse plate 38 in a manner to become apparent.

The rear cylindrical portion 43 is provided with an internal interrupted thread 52 (Fig. 4) adapted to mesh with the external interrupted thread 53 on the breechblock 4. The breechblock 4 contains a sleeve 54 in which is a chamber 55 and venturi orifices 56. Internally threaded rearward projection 52' extends from the sleeve 5 to act as a stop for the breechblock and to assist in proper engagement by the threads 52 of the sleeve and the interruption of the threads 53 of the breechblock, when the breechblock or rear gun section is swung back from its position in Fig. 5 to its position of alignment with the front gun section 3.

As shown in Figures 2, 11 and 12, each orifice 56 is formed from a pair of frusto-conical portions connected together end-to-end at their smaller bases to form a continuous passage for the discharge of the propellant gases. Each orifice as a unit is displaced in a direction opposite to the twist of the barrel rifling, in those weapons employing rifling.

Integral with the breechblock 4, and extending laterally therefrom, is a hollow rectangular bracket 57 having a bore 58 through which bracket 57 is rotatably mounted upon the slotted portion 39 of the shaft 36.

Extending transversely of the bore 58 is a locking pin or shaft 59 having flat sides 60 thereon by means of which the shaft 59 can be slid into final position in the shaft opening 40 and locked therein by rotating the hand lever 61 from a position fore-and-aft of the weapon to an upright position shown in the drawings (Fig. 14). A firing mechanism, generally indicated by reference numeral 62, is of the electrical contact type fed through a lead 65 from an electrical source, not shown, and having a plunger 63 forced by a coiled spring 64 into contact with the insulated ring 66 of a round of ammunition for electrically exploding the same in a manner explained in the previously mentioned co-pending application Serial No. 715,675, now Patent 2,492,279 dated December 27, 1949.

Operation

In Figures 1 and 2, the gun is shown with breechblock 4 in closed position preparatory to firing of the weapon. Upon ignition of the propellant charge, the projectile is projected forwardly out of the barrel and the frangible head 4' is disintegrated, allowing a portion of the propellant gases to be discharged rearwardly through the breechblock and out the venturi orifices 56.

The propellant gases passing rearwardly through the orifices 56 create a force in a direction to counteract the recoil caused by the projectile in being propelled from the gun. Also due to the inclination of the orifices 56 the thrust of the escaping propellant gases will be in such direction as to offset the tendency of the rifled barrel to twist in a direction opposite to the rotation of the projectile as it advances through the barrel. Obviously, the barrel may be rifled with a left or right hand twist and rotational reaction could be eliminated in either case by directing the inclination of the orifices in the opposite direction. Hence, the orifices counteract both the recoil and rotational reactions of the barrel caused by the longitudinal and the rotational movement of the projectile as

it is propelled through the barrel. The orifices not only counteract the twisting reaction of the barrel, but also exert a turning action upon the breechblock itself to maintain it in its locked position during firing.

The breechblock 4 is opened (or unlocked) by turning the hand lever 31 clockwise, indicated by the arrow in Figure 1. This will rotate the helical-toothed pinion 34, in mesh with the transverse leg 45 of the L-shaped gear sector 35, which in turn will rotate the locking sleeve 5 in a clockwise direction as viewed in Figure 8, for approximately $\frac{1}{6}$ of a revolution to disengage the interrupted threads 53 and 52, at which time the longer tooth 48 on the locking sleeve 5 will strike the tooth 37 on the shaft 36 to hold the locking sleeve 5 against further clockwise movement, as viewed in Figures 7 and 8, or angular downward movement as viewed in Figure 1. During the above operation, the shaft 27, and consequently the gear 34 and the shaft 36 are held from movement to the rear by the spring pressed detent 23' engaging the depression 29'.

As the locking sleeve 5 is restrained from rotation due to the engagement between the tooth 48 and the tooth 37, continued rotation of the hand lever 31 in a clockwise direction will cause the helical-toothed pinion 34 to engage the longitudinal leg 44 of the L-shaped gear section 35, the longitudinal leg 44 of the gear section 35 functioning as a gear rack with the pinion 34, to shift the locking sleeve 5 forwardly (to the right when viewed in Figures 1 and 3) to uncover and clear the breechblock external threads 52. Travel of the sleeve 5 is terminated by the plate 23, as shown in Figures 3 and 4, and the rear end of the sleeve 5 is now flush with the rear side of the chamber flange 9. This longitudinal travel of the locking sleeve 5 will simultaneously cause the tooth 37 to ride between the teeth 48 and 49, as shown by Figure 7.

At this point in the cycle of operation, the sleeve 5 and the longitudinal leg 44 of the gear sector 35 are thus held against rotation and forward motion. However, as the hand lever 31 and consequently the helical-toothed pinion 34 are continued to be rotated in the clockwise direction, viewed in Figure 1, the pinion 34 will now roll on the longitudinal leg 44 for the remainder of its length, carrying with it the gear case 32 and shafts 27 and 36 to the rear of the gun (to the left when viewed in Figures 3 and 4), overcoming the pressure of the spring-pressed detent 23', causing the same to ride out of the depression 29'. The breechblock 4, being secured to the shaft 36, will likewise be moved rearwardly, separating it from the gun chamber 7, as shown in Figure 4, until the spring-pressed detent 23' rides into the transverse slot 29'.

During this portion of the operating cycle, the operating hand lever 31 will have moved from its original position in Figure 1 approximately one complete revolution in a clockwise direction, coming to rest in a substantially vertical position shown by the dotted lines in Figure 4. In this position, the depending lug 31' is downward and clear of the flange 26' on the rearwardly-directed inclined member 26' as shown in Fig. 8.

The operating hand lever 31 can now be swung downwardly and outwardly, in a clockwise direction when viewing Figure 8, rotating the shafts 27 and 36 and gear case 32 to tilt the breechblock 4 away from and downwardly of the gun, as shown by Figure 5, until completely clearing it.

When the shaft 36 is rotated, the radial projection on plate 38 abuts the periphery of the projection 51, thereby holding the sleeve 5 and the shaft 36 against further rotation and in a position for the gear leg 44 to be brought back into mesh with the pinion 34 when the breechblock 4 is tilted back toward gun chamber 7 (i. e., from the Figure 5 to the Figure 3 position) preparatory to being locked by the sleeve 5.

In the particular embodiment shown, the removal of the expended round and the insertion of a new one is accomplished manually, after which the operating lever

31 is swung upwardly, or counterclockwise as in Figure 8, simultaneously causing rotation of the teeth 48 and 49 to align the teeth 53 with the peripheral spaces between the external teeth 52 of the locking sleeve 5, as shown in Figure 7, and to mesh the longitudinal leg 44 with the pinion 34.

Rotating the lever 31 counterclockwise, viewed in Figure 3, will cause the spring-pressed detent 23' to ride out of the slot 29', allowing the pinion 34 to roll along the longitudinal leg 44 of the gear section 35 until the breechblock 4 abuts the flange 9 of the chamber 7, as shown in Figure 3. Continued movement of the lever 31 in this counterclockwise direction will cause the pinion 34 to shift the sleeve 5 rearwardly until the enlarged part of the sleeve 15 5 covers the breechblock external teeth 53, at which time the annular surface 47 will abut the collar 9 and the pinion 20 will simultaneously engage the transverse leg 45 to rotate the sleeve causing interengagement between the interrupted teeth 52 and 53, as shown in Figures 2 and 6, to lock the breechblock 4 against the gun chamber 3.

Although the preferred embodiment has been disclosed, it is obvious that various modifications may be made without departing from the spirit and scope of the following claims:

25 I claim:

1. A recoilless artillery weapon comprising a gun tube having a flanged chamber and an externally threaded portion adjacent said chamber, a trunnion band including a generally cylindrical portion in threaded engagement with the threaded portion of said gun tube and a longitudinally parallel bearing cylinder, key means for releasably locking and angularly positioning said band to said tube, a cap forming a spaced closure for one end of said bearing cylinder, a spring pressed plunger projecting radially inwardly 35 on said bearing cylinder intermediate its length, a locking sleeve including a generally cylindrical, shouldered portion slidably and rotatably mounted for limited movement on said chamber and a locking ring integral with said sleeve and having an interrupted thread therein, a generally 40 L-shaped rack formed on the outer periphery of said shouldered portion, an operating shaft assembly comprising a cylindrical part journaled in said bearing cylinder for limited axial and rotational movement relative thereto and having a plurality of grooves therein selectively engageable with said plunger, a breechblock mounting part, 45 and an operating crank and helical pinion gear in mesh with said rack rotatably mounted between said breechblock mounting part and cylindrical part, and a generally cylindrical breechblock secured to said mounting part and including a flanged portion adapted to abut the outer 50 face of said chamber flange and having an external interrupted thread thereon, said locking sleeve being movable upon actuation of said crank, between two positions in one of which its interrupted thread engages that on said block and in the other of which said sleeve is disengaged 55 and axially spaced from said block whereby the latter may be swung about said breechblock mounting part, by continued movement of said crank, into breech open position, and a quick detachable connection between said breechblock and its mounting part.

2. An artillery weapon of the recoilless type comprising a gun tube having a flanged chamber and an externally threaded portion adjacent said chamber, a detachable trunnion band including a generally cylindrical portion in threaded engagement with a threaded portion of said gun tube and a longitudinally parallel bearing cylinder, key means for releasably locking said band to said tube, a cap forming a spaced closure for one end of said bearing cylinder, a spring pressed plunger projecting radially inwardly 65 on said bearing cylinder intermediate its length, a locking sleeve including a generally cylindrical, shouldered portion slidably and rotatably mounted for limited movement on said chamber and an integral locking ring having an interrupted thread therein, a generally L-shaped 70 rack formed on the outer periphery of said shouldered

portion, an operating shaft assembly comprising a cylindrical part journaled in said bearing cylinder for limited axial and rotational movement relative thereto and having a plurality of grooves therein selectively engageable with said plunger, a breech mounting part, and an operating crank and helical pinion gear in mesh with said rack rotatably mounted between said breechblock mounting part and said cylindrical part, and a generally cylindrical breechblock secured to said mounting part and including a flanged portion adapted to abut the outer face of said chamber flange and having an external interrupted thread thereon said locking sleeve being movable upon actuation of said crank, between two positions in one of which its interrupted thread engages that on said block and in the other of which said sleeve is disengaged and axially spaced from said block whereby the latter may be swung, by continued movement of said crank, into breech open position.

3. An artillery weapon comprising a gun tube having a chamber and an externally threaded portion adjacent said chamber, a removable trunnion band including a generally cylindrical portion in threaded engagement with the threaded portion of said gun tube and a longitudinally parallel bearing cylinder, a locking sleeve including a generally cylindrical shouldered portion slidably and rotatably mounted for limited movement on said chamber and an integral locking ring having an interrupted thread therein, a generally L-shaped rack formed on the outer periphery of said shouldered portion, an operating shaft assembly comprising a cylindrical part journaled in said bearing cylinder for limited axial and rotational movement relative thereto, a breech mounting part, and an operating crank and helical pinion gear in mesh with said rack rotatably mounted between said parts, and a generally cylindrical breechblock secured to said mounting part and having an external interrupted thread thereon, said locking sleeve being movable, upon actuation of said crank, into at least two positions in one of which its interrupted thread engages that on said block, and in the other of which said sleeve is disengaged and axially spaced from said block whereby the latter may be swung, by continued movement of said crank, into open position, said breechblock having

10 a quick detachable connection with said part on which it is mounted.

4. In a gun having a chamber and a breechblock movably mounted adjacent thereto and having locking means thereon, a mechanism for releasably locking said breechblock to said chamber comprising, a locking sleeve axially reciprocable and rotatable with respect to said chamber, locking means on said sleeve adapted to co-act with the locking means on said block, operating means movably mounted adjacent said chamber and adapted to be secured to said block, a helical pinion gear rotatably mounted on said operating means, and a generally L-shaped rack on said sleeve engaged with said pinion gear, said mechanism being constructed and arranged whereby initial rotation of said pinion gear rotates said sleeve to unlock the latter from the breech; further rotation of said pinion gear moves said sleeve a limited distance in an axial direction, and final continued rotation of said pinion gear moves said breechblock a limited distance in an opposite axial direction after movement of said sleeve has ceased.
